DISPOSAL SYSTEM

Elra Francis Howe, Chicago, Ill., assignor to
Joseph P. Graf

Application October 14, 1950, Serial No. 190,173

9 Claims. (Cl. 182—1)

1

This invention relates to a disposal system, and more particularly to a sewage disposal system wherein the collection tank may be below the level of the disposal pipe.

One feature of this invention is that it provides an improved disposal system; another feature of the invention is that it provides a disposal system wherein the collection tank and all of the disposal apparatus may be below the level of the disposal pipe; a further feature of the invention is that the collection tank is provided with a pocket of relatively small volume whereby the system is made more sensitive and positive in its operation; still another feature of the invention is that positive check valve means are provided to prevent any substantial reverse flow through the system; yet a further feature of the invention is that disintegrating means are provided for disintegrating any solid material which might reach and clog the pump of the apparatus; and still an additional feature of the invention is that substantially the entire system may be mounted below floor level where it is completely out of the way, while at the same time ready access may be had to the apparatus for purposes of cleaning or repair.

Other features and advantages will be apparent from the following description and from the drawings, in which:

Fig. 1 is a vertical section showing the disposal apparatus associated with a water closet; Fig. 2 is a top plan view of the apparatus of Fig. 1 with the water closet removed; Fig. 3 is a horizontal section along the line 3—3 of Fig. 1; Fig. 4 is an enlarged fragmentary vertical section along the line 4—4 of Fig. 3; Fig. 5 is a fragmentary section along the line 5—5 of Fig. 4; Fig. 6 is a transverse horizontal section along the line 6—6 of Fig. 4; Fig. 7 is a section along the line 7—7 of Fig. 4; and Fig. 8 is a top plan view of the pump impeller apparatus.

The disposal system disclosed and claimed herein is particularly adapted for use in a basement or the like, wherein the disposal or sewer pipe enters the building above the basement floor level. Heretofore it has not been possible to install a water closet, sewer, tub, sink, etc., in such a basement unless a large, expensive ejector unit was also installed. Such an ejector unit costs a very substantial amount and comprises a motor driven pumping system wherein bulky mechanisms are located above the floor of the basement, utilizing considerable space in the basement.

The system disclosed and claimed herein in-

2

cludes a float actuated motor-operated pump arrangement, all of the mechanisms being positioned below the basement floor level so that no space is utilized in the basement. In addition, the improved system can be installed for a small fraction of the cost of known ejector units and includes features and advantages not heretofore known in such units, as for example, a tank construction which results in high sensitivity and improved operation of the apparatus, a check valve arrangement for preventing back flow in any substantial amount, and disintegrator means for effecting the disintegration of any solid material which would reach the pump.

Certain of the mechanisms which may be employed in the system and which are illustrated in the system disclosed herein are similar to mechanisms shown and described in detail in my patent for a "Flood Control System," No. 2,421,066, which issued May 27, 1947. If desired, reference may be had to this patent for a more detailed disclosure of certain of the mechanisms. Reference may also be had to my co-pending application entitled "Flood Control System," filed August 26, 1949, as Serial No. 112,587, now Patent No. 2,569,102, issued September 25, 1951, for a disclosure of a flood control system utilizing some similar arrangements.

Referring now more particularly to the drawings, in Fig. 1 the basic apparatus is shown as being installed beneath a basement floor 10 and as being utilized with a water closet comprising a bowl 11 and a flush tank 12. A disposal or sewer pipe 13 enters the building above the level of the basement floor. Obviously with this arrangement, a conventional water closet drainage system would not be feasible.

The disposal apparatus comprises a housing having a sloping rear wall 14 beneath the water closet and having a vertical front wall 15, a base 16 and side walls 17 and 18. The housing, which may comprise an iron casting, is divided by a partition 20 into a collection tank 21 beneath the water closet and an apparatus compartment 22 forwardly of the water closet. The apparatus compartment has a readily removable cover 23 which may be secured by screws 24 onto an inwardly turned flange 25, and the collection tank has a removable plate 26 to permit access to the interior of the tank.

The partition 20 is so formed that it provides a pocket 27 in the tank 21, as seen best in Fig. 1. This pocket is of relatively small volume when compared with the volume of the tank, which may have an over-all volume of 35 or 40 gallons.

Inasmuch as the pocket joins with the sloping wall 14, it acts as a collector for liquid and solid material so that the solid material may become water-soaked and may be more easily disintegrated, as will be hereinafter described. The tank 21 has a top opening 28 for connection with the drain connector of the water closet, and the tank has a plugged opening 29 in at least one side for connection with some other drainage source, as for example, a tub, shower, etc. Another opening 30 in one side of the tank connects with an air vent pipe 30a which may lead out of the building in conventional manner.

On the other side of the partition 20 in the apparatus compartment 22, a motor 31 is mounted on a cylindrical mounting stand 32 which extends upwardly from a pump housing casting 33, the housing 33 being connected with the disposal pipe 13 by means of an outlet pipe 34 which provides a fluid passage communicating with the outlet of the pump and the disposal pipe. A conventional check valve 35 in the pipe 34 permits substantial flow only in the disposal direction from the pump to the disposal pipe.

In order to draw material from the pocket 27 of the collection tank 21, a pump is provided in the housing 33, and the inlet side of the pump is connected to the pocket 27 by a fluid passage designated at 36 in Fig. 4. The drive shaft 31a of the motor extends into the housing 33 and near the lower end of this shaft the pump impeller 40 (Fig. 8) is mounted, the pump being of the common centrifugal type having a centrally located intake 37 and an outlet 41 at the periphery of the pump housing, as shown in Fig. 8.

A plurality of disintegrator blades 42 are mounted on the shaft 31a within the housing 33 for rotation by the motor 31, these blades having portions extending between the parallel bars 43 of a grate, and said blades extending closely adjacent the inner wall of the pump housing 33 so that disintegration of solid material is accomplished as disclosed in my earlier patent above mentioned.

Rapid rotation of the disintegrator blades 42 will cause the water to spin around the pump inlet, centrifugal force keeping the water away from the centrally located inlet 37. In order to increase the efficiency of the pump, I provide a water guide between the disintegrating means and the intake of the pump for causing material to flow into the pump intake 37. The guide comprises a pair of stationary plates 44 and 45 of spiral formation arranged on opposite sides of the shaft 31a to define a tapering flow path into the pump intake as best seen in Fig. 7. These guides pick up the whirling stream of water developed by the disintegrator blades 42 and direct it into the center of the housing 33 and into the pump intake 37, thereby increasing the efficiency of the pump.

The motor 31 is operated by float actuated switch means generally similar in structure and function to those described in my earlier patent, the motor being connected to a source of power through a switch which is controlled by a float. This motor control means comprises a float 46 in the pocket 27 and connected by a shaft 47 to switch means within a switch housing 48. This float operated switch device may comprise a conventional commercially obtainable "Magnetrol" mercury type switch and may be similar to that of my earlier patent. The power leads extend through a conduit 50 out of the appa-

ratus chamber and make connection with an outside source of voltage, as for example, conventional commercial 110 volt A. C., through a master control switch 51 which may be mounted at any convenient location.

In the operation of the disposal system, when water and solid material enter the collection tank 21 they collect in the pocket 27, which is purposely of relatively small volume when compared to the volume of the tank 21, so that when only a gallon or so of water enters the pocket the float 46 is raised sufficiently to close the magnetrol switch in the housing 48 and start the motor 31 (assuming, of course, that the master switch 51 is closed). The motor will drive the pump impeller 40 and the disintegrator blades 42 so that as the water flows toward the pump intake solid material will be disintegrated and will not clog the pump. The relatively small size of the pocket 27 assures that all solids will be soaked in water to facilitate disintegration, since there is normally some water in said pocket as indicated by the dashed line in Figs. 1 and 4. The water and other material is passed through the pump and out the pipe 34, past the check valve 35, and to the disposal pipe 13. In the apparatus disclosed in Fig. 1, the pump will normally operate for about 20 seconds each time the apparatus is actuated. It is important to position the float so that the shut-off position of the float—i. e., the position of the float when the magnetrol switch is opened as the float descends—is above the bottom of the passageway 36 in order to remove any possibility that the pump would be connected to operate all of the time.

The system disclosed herein provides a novel and efficient disposal system, particularly adapted for use where the sewage pipe or other disposal pipe enters the building above the basement floor. Because of the check valve 35 there is no possibility of back flow which would cause flooding, and the system is completely automatic in operation and when installed utilizes almost no space above the basement floor level, the only parts extending above the floor level being the outlet pipe 34 and the electric conduit 50. The cover 23 may be readily removed to obtain access to the apparatus compartment, and the plate 26 may be readily removed to permit cleaning of the grate if necessary.

While I have shown and described certain embodiments of my invention, it is to be understood that it is capable of many modifications. Changes, therefore, in the construction and arrangement may be made without departing from the spirit and scope of the invention as disclosed in the appended claims.

I claim:

1. A disposal system associated with a disposal pipe, including: a collection tank having an offset portion providing a pocket of relatively small volume compared to the volume of said tank, said pocket being so placed that substantially all liquid entering said tank flows immediately into said pocket; a pump; a first fluid passage communicating with said pocket and the inlet of said pump; a second fluid passage communicating with the outlet of said pump and said disposal pipe; motor means for operating said pump; and motor actuating means responsive to the liquid level in said pocket for controlling the operation of said motor means.
2. A disposal system associated with a disposal pipe, including: a collection tank having an off-

set portion providing a pocket of relatively small volume compared to the volume of said tank, said pocket being so placed that substantially all liquid entering said tank flows immediately into said pocket; a pump; a first fluid passage communicating with said pocket and the inlet of said pump; a second fluid passage communicating with the outlet of said pump and said disposal pipe; a check valve in said second passage permitting substantial flow only in the disposal direction from said pump to said disposal pipe; motor means for operating said pump; and motor actuating means responsive to the liquid level in said pocket for controlling the operation of said motor means, said motor actuating means comprising a float in said pocket and switch means operated thereby, at least the pocket of said tank, said pump and motor means being below the level of said disposal pipe.

3. A sewage disposal system associated with a disposal pipe, including: a housing adapted to be positioned under a floor below the level of said disposal pipe, said housing having a partition providing a collection tank on one side thereof and an apparatus compartment on the other side thereof, said collection tank having a small offset pocket at substantially the bottom thereof so that substantially all liquid entering said tank flows immediately into said pocket; a pump in said compartment; a first fluid passage communicating with said pocket and the inlet of said pump; a grate comprising a plurality of spaced parallel bars extending transversely of said passage; a pipe providing a second fluid passage communicating with the outlet of said pump and said disposal pipe; a check valve in said pipe permitting substantial flow only in the disposal direction from said pump to said disposal pipe; a motor in said compartment for operating said pump; a plurality of rotatable blades positioned between said grate and the inlet of said pump, said blades operated by said motor and a portion of each of said blades projecting through said grate during part of each cycle of rotation for effecting the disintegration of any solid material which would reach the pump; motor actuating means responsive to the liquid level in said pocket for controlling the operation of said motor means, comprising a float in said pocket, switch means in said compartment, means connecting said float and switch means whereby said switch means are operated by said float, the float and switch means being so arranged that the motor shut-off position of the float is above the bottom of said first passage; and readily removable cover means for said housing to permit access to said grate and to said motor, pump and switch means.

4. A sewage disposal system associated with a disposal pipe, including: a housing adapted to be positioned under a floor, below the level of said disposal pipe, said housing having a partition providing a collection tank on one side thereof and an apparatus compartment on the other side thereof, said collection tank having an offset portion providing a pocket of relatively small volume compared to the volume of said tank, said tank including a flow guiding means to direct substantially all liquid entering said tank into said pocket; a pump in said compartment; a first fluid passage communicating with said pocket and the inlet of said pump; motor means in said compartment for operating said pump; motor actuating means responsive to the liquid level in said pocket for controlling the opera-

tion of said motor means; and a pipe providing a second fluid passage communicating with the outlet of said pump and said disposal pipe.

5. A sewage disposal system associated with a disposal pipe, including: a housing adapted to be positioned under a floor below the level of said disposal pipe, said housing having a partition providing a collection tank on one side thereof and an apparatus compartment on the other side thereof, said collection tank having an offset pocket of relatively small volume compared to the volume of said tank, said pocket being placed on substantially the bottom of said tank so that substantially all liquid entering said tank flows immediately into said pocket; a pump in said compartment; a first fluid passage communicating with said pocket and the inlet of said pump; motor means in said compartment for operating said pump; motor actuating means responsive to the liquid level in said pocket for controlling the operation of said motor means, said motor actuating means comprising a float in said pocket, switch means in said compartment, and means connecting said float to said switch means whereby the float operates the switch means, the motor shut-off position of float being above the bottom of said first passage; and a pipe providing a second fluid passage communicating with the outlet of said pump and said disposal pipe.

6. A sewage disposal system associated with a disposal pipe, including: a housing adapted to be positioned under a floor below the level of said disposal pipe and to have a toilet mounted on the top thereof, said housing having a partition providing a collection tank on one side thereof and an apparatus compartment on the other side thereof, said collection tank having an offset pocket of relatively small volume compared to the volume of said tank, said pocket being placed on substantially the bottom of said tank so that substantially all liquid entering said tank flows immediately into said pocket; a pump in said compartment; a first fluid passage communicating with said pocket and the inlet of said pump; a grate comprising a plurality of spaced parallel bars extending transversely of said passage; a pipe providing a second fluid passage communicating with the outlet of said pump and said disposal pipe; a check valve in said pipe permitting substantial flow only in the disposal direction from said pump to said disposal pipe; a motor in said compartment for operating said pump; a plurality of rotatable blades positioned between said grate and the inlet of said pump, said blades operated by said motor and a portion of each of said blades projecting through said grate during part of each cycle of rotation for effecting a disintegration of any solid material which would reach the pump; motor actuating means responsive to the liquid level in said pocket for controlling the operation of said motor means, comprising a float in said pocket, switch means in said compartment, means connecting said float and switch means whereby said switch means are operated by said float, the float and switch means being so arranged that the motor shut-off position of the float is above the bottom of said first passage; and readily removable cover means for said housing to permit access to said grate and to said motor, pump and switch means.

7. A sewage disposal system associated with a disposal pipe, including: a housing adapted to be positioned under a floor below the level of said disposal pipe; a drain conduit in the top

of said housing; a partition in said housing providing an apparatus compartment on one side thereof and a collection tank on the other side thereof, said collection tank having an offset pocket of relatively small volume compared to the volume of said tank, said pocket being on substantially the bottom of said tank, and said tank having a downwardly sloping wall adapted to carry substantially all flow of liquid from said drain immediately to said pocket; a first fluid passage communicating with said pocket and the inlet of said pump; motor means in said compartment for operating said pump; motor actuating means responsive to the liquid level in said pocket, said means comprising a float in said pocket, switch means in said compartment, and means connecting said float to said switch means whereby the float operates the switch means, the motor shutoff position of the float being above the bottom of said first passage; and a pipe providing a second fluid passage communicating with the outlet of said pump and said disposal pipe.

8. A disposal system associated with a disposal pipe, including: a collection tank having an offset pocket of relatively small volume compared to the volume of said tank, said pocket being

placed on substantially the bottom of said tank so that substantially all liquid entering said tank flows immediately into said pocket; a pump; a first fluid passage communicating with said pocket and the inlet of said pump; a second fluid passage communicating with the outlet of said pump and said disposal pipe; motor means for operating said pump; and motor actuating means responsive to the liquid level in said pocket for controlling the operation of said motor means.

9. Apparatus of the character claimed in claim 8 wherein said motor actuating means comprises a float in said pocket and switch means operated thereby, the motor shut-off position of the float being above the bottom of said first fluid passage.
